UNITED STATES PATENT OFFICE.

FRANCIS GINNASI, OF NEW YORK, N. Y.

ACETYLENE-GAS GENERATOR.

SPECIFICATION forming part of Letters Patent No. 613,901, dated November 8, 1898.

Application filed April 18, 1898. Serial No. 677,912. (No model.)

To all whom it may concern:

Be it known that I, FRANCIS GINNASI, a citizen of the United States, and a resident of New York city, county of New York, and State 5 of New York, have invented certain new and useful Improvements in Acetylene-Gas Generators, of which the following is a specification, reference being had to the accompanying drawing, forming a part thereof, in which 10 similar letters of reference indicate corresponding parts.

This invention relates to an improvement in acetylene-gas generators; and the object thereof is to provide simple inexpensive means 15 for automatically regulating the generation of gas from the carbid of calcium.

The invention consists in the features, combinations, and details of construction, and will be hereinafter fully described, and specifically set forth in the annexed claims.

In the accompanying drawing the figure is a central sectional elevation of the device.

In applying my invention I employ a gasometer a of the usual type, embodying the outer cylinder a , preferably mounted on legs a' and being open at the top, and an inner cylinder a^2 , closed at the top and open at the bottom and adapted to telescope within the outer cylinder. Stand-pipes b b' , fixed in suitable 20 apertures in the base of the outer cylinder, are adapted to convey gas to and from, respectively, the interior of the gasometer. The escape of gas is prevented by a body of water contained within the outer cylinder in the 25 usual manner.

Fixed to the top of the interior cylinder are the blocks a^3 a^3 , which support the arm a^4 , projecting beyond the outer wall of the gasometer.

40 A receptacle C , adapted to contain the carbid of calcium or other analogous gas-producing material, is placed, preferably, in close proximity to the gasometer and has an open mouth adapted to be closed by means of the gas-tight stopper c , which is retained in position by frictional contact with the interior of the neck of the receptacle until a dangerous pressure is generated within the receptacle, when it will be blown out.

45 Into an aperture c' of the stopper a flexible tube B is tightly fitted, and the free end of this

tube is connected with the stand-pipe b in any approved manner.

Stop-cocks b^2 b^3 are fitted to the stand-pipes b b' , respectively, preferably close to the sides 55 of the gasometer, outside the elbows.

A central hole c^2 in the stopper c is adapted to receive the nozzle d of a flexible water-reservoir D . This nozzle is provided with the stop-cock d' , adapted to regulate the size of 60 the aperture communicating between the water-reservoir and the carbid-receptacle. Obviously the flow of water may be cut off entirely, if desired.

The upper portion of the water-reservoir is 65 adapted for intermittent contact with the arm a^4 , carried by the gasometer.

In operation the carbid of calcium is placed in the receptacle C , the stopper carrying the tube B placed in position, and the water reservoir filled and its nozzle inserted in the hole c^2 . The stop-cock d' is adjusted so that when there is no pressure upon the water-reservoir no water drops into the carbid-chamber; but as soon as the arm a^4 contacts with the reservoir 70 drops of water are forced through the nozzle into the carbid-receptacle, where it frees the gas, which passes through the tube B and stand-pipe b into the gasometer. The inner cylinder then rises, carrying with it the 75 arm a^4 and relieving the pressure on the water-reservoir. Generation of gas ceases. As soon, however, as the stop-cock b^3 is opened and the gas passes out from the gasometer to the burner the cylinder a^2 falls by gravity 80 and the arm a^4 again comes in contact with the water-reservoir D and gas generation 85 again commences. This action will be continued automatically until the supply of water or carbid of calcium is exhausted. 90

Having thus described my said invention, what I claim as new, and desire to secure by Letters Patent, is—

1. An automatic gas-generator, embodying a receptacle for the gas-producing material, 95 a flexible water-reservoir mounted thereon, a gasometer, and means actuated by the gasometer for automatically regulating the production of gas, substantially as shown and described. 100

2. In an automatic gas-generator, the combination of a receptacle for the gas-producing

material, a flexible water-reservoir mounted thereon and means for preventing abnormal pressure in the receptacle, substantially as shown and described.

- 5 3. An automatic gas-generator, embodying a gasometer, an arm carried thereby, a flexible water-reservoir adapted for intermittent contact with said arm, means for regulating the discharge of water from said reservoir, a 10 receptacle for the gas-producing material and means for conveying the gas from the generator to the gasometer, substantially as shown and described.
4. An automatic gas-generator, embodying 15 a receptacle for the gas-producing material,

a stopper therefor, a valve-controlled flexible water-reservoir mounted thereon, a gasometer, an arm mounted thereon and adapted for intermittent contact with the water-reservoir and a flexible pipe communicating between 20 said receptacle and said gasometer, substantially as shown and described.

In testimony that I claim the foregoing as my invention I have signed my name, in presence of two witnesses, this 14th day of 25 April, 1898.

FRANCIS GINNASI.
